EDGAR M. BUTLER AND GEORGE A. JOCHUM, OF BROOKLYN, NEW YORK.

DUMB-WAITER ATTACHMENT.

1,404,832.

Specification of Letters Patent. Patented Jan. 31, 1922.

Application filed December 29, 1920. Serial No. 433,772.

To all whom it may concern:

Be it known that we, EDGAR M. BUTLER and GEORGE A. JOCHUM, citizens of the United States, both residing at New York 5 city, borough of Brooklyn, in the county of Kings and State of New York, have invented a certain new and useful Dumb-Waiter Attachment, of which the following is a specification.

10 This invention is an attachment for dumb waiters and is particularly adapted to be employed in conjunction with dumb waiters used in apartment houses and other buildings. 15 In dumb waiter installation in apartment houses and elsewhere, the dumb waiter, which is suspended on a rope or cable, is adapted to travel in a shaft which extends from the cellar to the roof of the structure 20 and doors or openings are provided at the respective floors to permit articles to be positioned on or removed from the dumb waiter at any floor.

Dumb waiters of the character described 25 are used more especially in the collection of refuse, garbage, ashes, etc. in their removal to the cellar or basement of the building and in the delivery of foods, ice, milk, etc., throughout the building from the base- 30 ment. As dumb waiters are now constructed, they are usually provided with a flat top having an eye bolt at its center to which the cable or hoisting rope is attached and in practically every instance the top is formed 35 with a raised border or frame. This construction results in the formation of a dust catcher on top of the dumb waiter and since the raised border precludes articles placed on top of the dumb waiter from falling off, 40 it has become the practice in the larger cities for milkmen to place the milk bottles for the various families on top of the dumb waiter and in the dust and dirt which collects thereon. The milk bottles are usually 45 wet from ice packings in the delivery wagons and such water drains off the bottles on to the top of the dumb waiter, forms the dust thereon into mud which sifts through the top of the dumb waiter into the interior 50 thereof and on to articles positioned within the dumb waiter, thereby producing a very unsanitary condition. This is particularly true in large apartment houses where care- 55 less tenants indulge in the practice of throwing sweepings, combings, cigarette and cigar butts and other waste material down the

dumb waiter shaft. Manifestly, this waste material is collected on top of the dumb waiter and when the milk bottles are removed by the respective tenants, this dirt 60 sticks to the bottle and is carried thereby into the apartment.

Furthermore, the practice of throwing cigarette butts into the shaft has resulted in a large number of fires due to the ignition 65 of the waste material on top of the dumb waiter by the lighted butts.

With the foregoing considerations in mind, the object of the present invention is to provide a simple attachment for dumb 70 waiters which attachment may be readily installed on any dumb waiter of corresponding size and is adapted, not only to overcome the improper practice of delivering milk bottles on top of the dumb waiter, but also pre- 75 cludes material thrown down the shaft from lodging on the top of the dumb waiter, thereby rendering the dumb waiter more sanitary than heretofore.

With this general object in view, the present invention in its preferred embodiment consists in a metallic cover or hood of substantially pyramidal shape provided at its apex with an aperture adapted to embrace the housing rope or cable of the dumb waiter 80 and having at its base a depending flange or skirt adapted to embrace the upper edge of the dumb waiter, so as to centralize the hood and impart a more finished appearance to the assemblage. In practice, the hood is 85 preferably divided into two sections which sections are adapted to be separated for convenience in installing the hood on a dumb waiter without necessitating the detachment of the hoisting rope or cable and thereafter 90 secured together when the hood is in place thereon to maintain the parts in assembled 95 relation.

Features of the invention, other than those adverted to, will be apparent from the hereinafter detailed description and claims, when read in conjunction with the accompanying drawings.

The accompanying drawings illustrate one practical embodiment of the invention, 105 but the construction therein shown is to be understood as illustrative, only, and not as defining the limits of the invention.

Figure 1 is a perspective view of a dumb waiter showing the same mounted for vertical movement in a shaft, the walls of which are broken away in the interest of clearness. 110

In this figure, an attachment embodying the present invention is illustrated as associated with the dumb waiter.

Figure 2 is a perspective view of the attachment removed from the dumb waiter; and,

Figure 3 is a plan view of the attachment shown in Figure 2.

Referring to the drawings, 1 designates 10 a dumb waiter installed in a shaft 2 and mounted for movement on guides 3 and 4 and adapted to be supported by a rope or cable 5. The structure illustrated is that 15 of a conventional installation and may be varied without in anywise effecting the invention which relates purely to an attachment 6 shown as superimposed on the dumb waiter in Figure 1.

The attachment 6 is preferably formed 20 from sheet metal, and while its shape may differ from that shown in the drawings, it is 25 preferably of the pyramidal form illustrated in the drawings. The attachment, which may be termed a hood, is provided at its apex 30 with a hole 7 through which the rope or cable 5 is adapted to pass and the four sides of the base of the hood are provided with a depending flange or skirt 8 which is adapted to overlie the upper edge of the dumb waiter 35 as clearly shown in Figure 1 to centralize the hood on the dumb waiter and impart a finished appearance to the assemblage.

In order to permit the hood to be positioned on the dumb waiter without necessitating the disconnecting of the cable 5 therefrom, the hood is preferably split diagonally along the line 9, so that it is formed, in effect, in two parts, whereby the parts may be brought together from the opposite sides 40 of the cable 5 in assembling the hood on the dumb waiter. In order to normally hold the parts in assembled relation, the adjacent edges of the two sections are provided with aligned curls 10 similar to those common in 45 hinge construction, some of which are formed on one section and some on the other, so that when the sections are assembled with the curls 10 in aligned relation, pins 11 may be forced therethrough for the purpose of holding 50 the parts together. The means described forms a convenient and inexpensive manner of attachment, though, if desired, the parts may be otherwise secured together. It is furthermore entirely within the scope of the 55 invention to otherwise form the hood so as to obviate the necessity of releasing cable 5 from the dumb waiter in order to install the attachment and the construction shown is for the purpose of illustration only.

60 It will be apparent from the foregoing description that the attachment of the present invention may be readily and expeditiously associated with any dumb waiter installation, and, in practice, the attachment may be 65 made in different sizes to fit dumb waiters of

varying sizes. In any event, the device is efficient in the carrying out of its intended functions of precluding improper use of the dumb waiter, more specifically the carrying of articles on the top thereof, as well as the 70 lodging of waste material on the top of the dumb waiter. The sloping sides of the hood will deflect material beyond the side of the dumb waiter so that it will fall to the bottom of the shaft where it may be removed from 75 time to time by the janitor. The top of the dumb waiter is thus kept in a perfectly sanitary condition at all times.

The present invention also achieves an additional result to those hereinbefore stated 80 in that the hood will act as a damper in the dumb waiter shaft in the event of fire in the building. It is not unusual in apartment house fires for fire to move from floor to floor through the dumb waiter shaft, but if 85 a dumb waiter equipped with the present invention is in the shaft above the floor where the fire starts the metal hood which substantially fills the shaft will act as a damper to keep down the flames and even though the 90 dumb waiter burns away, the cable 5 will still support the hood in the position of a damper within the shaft.

It will be manifest to those skilled in the 95 art that the invention is capable of modification to adapt it to different makes or kinds of dumb waiters used in the various environments and since these modifications will be 100 apparent to a skilled mechanic, it is not deemed necessary to show the invention in more than one of its forms. The invention is to be understood, however, as broadly novel as is commensurate with the appended claims.

In the foregoing description of the specific 105 form of the present invention illustrated, the same has been described as preferably made of sheet metal, although, in practice, the same may be constructed from wood, cardboard, or any other suitable material and may be satisfactorily fabricated from asbestos board or some other fibrous nonflammable material without departing from the spirit of this invention. Moreover, we have described the present invention as particularly intended to be used as an attachment, 115 thereby facilitating its positioning on a dumb waiter already installed. However, if desired, the present invention may be incorporated in dumb waiter construction at the time of installation and form a part of the 120 dumb waiter instead of an attachment therefor as hereinbefore pointed out.

Having thus fully described the invention, what we claim as new and desire to secure by Letters Patent is:

1. An attachment for dumb waiters embodying a hood adapted to seat on top of a dumb waiter and provided with an aperture through which the lifting rope of the dumb waiter is adapted to pass.

2. An attachment for dumb waiters embodying a hood provided with sloping sides and adapted to be loosely seated on the top of a dumb waiter, whereby extraneous materials falling on the dumb waiter are shed by the hood.

3. A dumb waiter attachment embodying a hood adapted to be seated on the top of a dumb waiter and divided into a plurality 10 of sections to permit of the positioning of the hood on the dumb waiter without necessitating the removal of the lifting cable of the dumb waiter.

4. An attachment for dumb waiters embodying a canopy having a sliding top and adapted to cover the top of a dumb waiter and provided with an aperture through which the lifting cable of the dumb waiter is adapted to pass.

20 5. An attachment for dumb waiters embodying a canopy adapted to cover the top of the dumb waiter and provided with an aperture through which the lifting cable of the dumb waiter passes, said canopy being 25 entirely independent of the dumb waiter construction.

6. An assembly of the character described embodying a dumb waiter, and a lifting cable associated therewith, in com-

bination with a canopy covering the top of 30 the dumb waiter and provided with an aperture through which the lifting cable of the dumb waiter passes, said canopy being adapted on its lower edge to overlie the upper edge of the dumb waiter.

35

7. A dumb waiter attachment embodying a hood of square pyramidal conformation adapted to seat on the top of a dumb waiter and provided at its apex with an aperture through which the lifting cable of the dumb 40 waiter is adapted to pass.

8. A dumb waiter attachment embodying a metallic hood of square pyramidal conformation adapted to seat on the top of a dumb waiter and provided at its apex with 45 an aperture through which the lifting cable of the dumb waiter is adapted to pass, said hood being divided in a diagonal plane passing therethrough into two halves, the adjacent edges of which two halves are formed 50 with complementarily curled portions adapted to receive locking pins for the purpose of detachably securing the sections in place in the dumb waiter.

In testimony whereof, we have signed 55 our names to this specification.

EDGAR M. BUTLER.
GEO. A. JOCHUM.
